R. VACHIER

CLARIFIER FOR SACCHARINE SOLUTIONS

Filed Oct. 15, 1925

Patented Mar. 23, 1926.

1,578,221

UNITED STATES PATENT OFFICE.

RAFAEL VACHIER, OF BATON ROUGE, LOUISIANA.

CLARIFIER FOR SACCHARINE SOLUTIONS.

Application filed October 15, 1925. Serial No. 62,638.

To all whom it may concern:

Be it known that I, RAFAEL VACHIER, a citizen of the United States, residing at Baton Rouge, in the parish of East Baton Rouge and State of Louisiana, have invented certain new and useful Improvements in Clarifiers for Saccharine Solutions; and I do hereby declare the following to be a full, clear, and exact description of the invention, such as will enable others skilled in the art to which it appertains to make and use the same.

My present invention relates to improvements in clarifiers for saccharine solutions, and more especially for the clarification of the raw juice from sugar cane. Such juice coming from the mill ordinarily carries with it more or less solid matter in the form of small pieces of bagasse, fragments of leaves, wax, scale, as well as more or less dust or mud from the field, which adheres to the stalks and passes through the mill with the stalks, being washed away with the juice and maceration water.

These solid particles tend either to fall by gravity in the juice when quiescent or to form a scum, and this scum is increased by the coagulation of the albumen when the raw juice is subjected to high enough temperature to coagulate the same.

The separation of the solid particles either upwards or downwards is further facilitated by the addition of lime or other chemicals well known in the sugar art.

My invention is especially intended to separate the scum at the top of the clarifier, the mud at the bottom of the clarifier, and to draw off the clear liquid from which these solid particles have been removed for subsequent evaporation and further treatment, well known in this art.

My invention will be more fully understood after reference to the accompanying drawings, in which I illustrate the central vertical section through the clarifier with the connections therefrom diagrammatically shown.

The clarifier is provided with an outer shell having the central cylindrical liquid chamber A, having the inner bottom A' in the form of an inverted truncated cone open at its center as at a'. Below this bottom A' there is another inverted truncated cone, forming with the bottom A' the mud chamber A'', which is also provided with a

central opening a'' at the bottom. The upper end of the liquid chamber is partly closed by the truncated cone A'', forming a scum chamber, which is open at the top and terminates in the hollow cylinder A'.

Mounted within the shell are a series of hopper like baffle cones B, B', B'' and B'', which are secured at their upper edges to the interior of the shell and are provided at their lower ends with hollow cylindrical ducts b, b', b'' and b''. The outer shell is also provided with suitable manholes A° for cleaning purposes, and with suitable wash holes a°, these being ordinarily provided with removable water-tight covers.

The raw juice is admitted through the inlet pipe C from the flash tank D, which is supplied with juice from the mills through the pipe D'. This pipe C terminates at its lower end in the circular pipe C', provided with a series of perforations c. The discharge pipe for the scum E has its inner end e projecting upwards in the center of the ring C', and telescoping over this end e is a sleeve f of the scum cone F. This scum cone is preferably made vertically adjustable, as by the slings g and screw G, which screw engages the handwheel H, which is internally screw-threaded to engage said screw G and bears upon the beam I, spanning the open top of the cylinder A'. By turning this handwheel H, the scum cone may be raised or lowered, as desired, so that the top of said cone may be adjusted to the desired height above the normal level of the juice in the cistern indicated by the line x-x.

The juice is heated in the upper part of the clarifier by means of the steam coil J fed with heat medium through the pipe J', and the condensed steam and vapor is carried off through the steam trap J'' to the hot well, not shown. Lime or other reagents may be admitted to the partly clear liquid at the bottom of the cone B by means of the annular pipe K, having the nozzles k, which pipe K is supplied with lime or other reagent through the pipe K' from the constant pressure re-agent supply tank L, which is supplied with said re-agent through the pipe L'.

M represents the clear juice trough, which receives its clear juice through the pipes N, N', N'' and N''' from the upper end of the V-shaped annular chambers, formed by the baffle cones and the outer shell of the clar-

2
fier. The juice is carried off from this clear juice trough for further treatment, as well known in the art.

Suitable test cocks O may be provided at any portion of the shell, and preferably in the lower portion thereof, as shown. Journalled in the axis of the mud chamber I provide a hollow rotary shaft P, perforated as at p, to permit the flow of water therefrom, which water is supplied through the pipe Q, connected to the lower end of the hollow shaft P, as by means of the stuffing box q. This shaft P is supported on the anti-friction bearings R. This shaft carries a worm-wheel S driven by the worm S', so that the shaft may be given a slow rotary motion. This hollow shaft P carries arms T and T', to which the scrapers U are connected, adjustment being given to these scrapers by means of the stays V and turn buckles v. These scrapers U rotate inside of the conical mud chamber.

The shaft P also has clamped or otherwise secured thereon the hub W, to which the scrapers W' are attached, which scrapers rotate above the conical bottom A'. The top of the shaft carries a dispersion cone X. Water for liquidation may be supplied through the pipe Y and the mud and water are carried off through the mud pipe Z, which may be spread out, if desired through the spray pipe z.

Suitable valves are supplied to the apparatus wherever needed.

Having thus described the construction of the apparatus in detail, its operation can now be explained.

The raw juice from the mills flows into the flash tank, and thence quietly into the upper portion of the scum chamber, the scum rising above the normal level x-x of the liquid will overflow into the scum cone F, and be carried off. As some juices yield more scum, or thicker scum than others, it is desirable to have the overflow scum cone vertically adjustable. The heating coil in the lower portion of the scum chamber will coagulate the albumen, and this will tend to rise carrying along with it other solid particles, such as wax, pectins, bagacillo, etc., thus adding to the scum rising above the normal level of the liquid and overflowing into the scum cone.

After the liquid passes downward through the heating zone, a certain quantity of a desired re-agent, such as lime, soda ash, phosphoric acid or any other convenient acid or alkali required to bring about the point of maximum clarification is sprayed into the liquid through the nozzles k.

By applying the re-agent at this stage of the process a distinct advantage is gained, due to the fact that some of the impurities might be re-dissolved if said saccharine liquid is subjected to the ultimate reaction

before the liquid is heated to the desired temperature.

As the liquid flows downwards, the baffle cones and the open cylinders at their ends will tend to direct the heavier solid particles downward, permitting the clear liquid to flow up into the V-shaped annular spaces between the exterior of the baffle cones and the outer shell, and this clear liquid will overflow by gravity into the clear juice trough M, whence it will be carried off for the subsequent operations of evaporating, etc., well known in the art.

The mud and heavier particles of solid matter will pass around the dispersion cone X, part of the solid matter dropping on the inclined bottom W', and the rest finding its way into the mud chamber below.

This chamber is as completely enclosed as possible, in order to keep the decanted impurities from being upset by the eddy and other currents on the uppermost layers of liquid and also enabling one to obtain said impurities in the most consistent way.

As the mud accumulates it may be scraped off by the scrapers U and W', and it may be drawn off through the drain pipe Z.

In order to facilitate cleaning out the bottom of the clarifier, water may be supplied under pressure through the pipe Q and sprayed through the openings p in the hollow shaft P. Also, water may be sprayed in through the jet z into the drain passage Z. Water or other liquids may also be applied through the liquidation pipes Y.

Suitable manholes A^o are provided for the admission of a man to wash out or repair the interior of the clarifier, and suitable wash holes a^o are also provided to facilitate cleaning out the interior of the apparatus.

It will be obvious that various modifications might be made in the herein described apparatus and in the construction, combination and arrangement of parts, which could be used without departing from the spirit of my invention, and I do not mean to limit the invention to such details, except as particularly pointed out in the claims.

Having thus described my invention, what I claim and desire to secure by Letters Patent of the United States is:

1. A clarifier for saccharine solutions comprising an outer shell having a central cylindrical liquid chamber with a downwardly inclined conical bottom open at its center, a lower mud chamber in the form of an inverted hollow truncated cone, below said bottom, and an upper scum chamber in the form of a truncated hollow cone, means for supplying the liquid to be clarified to said scum chamber, means for heating the liquid in said scum chamber, a series of inverted truncated hollow baffle cones projecting downwardly into said shell, and each provided with a cylindrical band at its lower

open end, a vertical adjustable scum overflow cone mounted in the scum chamber, with means for carrying off the scum from said overflow cone, means for carrying off the clear liquid from the upper portions of the V-shaped annular spaces between said baffle cones and the outer shell, a rotary hollow perforated shaft projecting up through the axis of the mud chamber, scrapers carried by said shaft for scraping the bottoms of said liquid chamber and of said mud chamber, means for supplying water under pressure to said shaft, means for rotating said shaft, and means for carrying off the mud and liquid contents from the bottom of said mud chamber.

2. A clarifier for saccharine solutions comprising an outer shell having a central cylindrical liquid chamber with a downwardly inclined conical bottom open at its center, a lower mud chamber in the form of an inverted hollow truncated cone, below said bottom, and an upper scum chamber in the form of a truncated hollow cone, means for supplying the liquid to be clarified to said scum chamber, means for heating the liquid in said scum chamber, means for injecting a reagent into the liquid below the heating zone, a series of inverted truncated hollow baffle cones projecting downwardly into said shell, and each provided with a cylindrical band at its lower open end, a vertically adjustable scum overflow cone mounted in the scum chamber, with means for carrying off the scum from said overflow cone, means for carrying off the clear liquid from the upper portions of the V-shaped annular spaces between said baffle cones and the outer shell, a rotary hollow perforated shaft projecting up through the axis of the mud chamber, scrapers carried by said shaft for scraping the bottoms of said liquid chamber and of said mud chamber, means for rotating said shaft, and means for carrying off the mud and liquid contents from the bottom of said mud chamber.

3. A clarifier for saccharine solutions comprising an outer shell having a central cylindrical liquid chamber with a downwardly inclined conical bottom open at its center, a lower mud chamber in the form of an inverted hollow truncated cone, below said bottom, and an upper scum chamber in the form of a truncated hollow cone, means for supplying the liquid to be clarified to said scum chamber, means for heating the liquid in said scum chamber, means for injecting a reagent into said liquid below said heating zone, a series of inverted truncated hollow baffle cones projecting downwardly into said shell, and each provided with a cylindrical band at its lower open end, a vertically adjustable scum overflow cone mounted in the

scum chamber, with means for carrying off the scum from said overflow cone, means for carrying off the clear liquid from the upper portions of the V-shaped annular spaces between said baffle cones and the outer shell, a rotary shaft projecting up through the axis of the mud chamber, scrapers carried by said shaft for scraping the bottoms of said liquid chamber and of said mud chamber, means for rotating said shaft, and means for carrying off the mud and liquid contents from the bottom of said mud chamber.

4. A clarifier for saccharine solutions comprising an outer shell having a central cylindrical liquid chamber with a downwardly inclined conical bottom open at its center, a lower mud chamber in the form of an inverted hollow truncated cone, below said bottom, and an upper scum chamber in the form of a truncated hollow cone, means for supplying the liquid to be clarified to said scum chamber, means for heating the liquid in said scum chamber, a series of inverted truncated hollow baffle cones projecting downwardly into said shell, and each provided with a cylindrical band at its lower open end, a vertically adjustable scum overflow cone mounted in the scum chamber, with means for carrying off the scum from said overflow cone, means for carrying off the clear liquid from the upper portions of the V-shaped annular spaces between said baffle cones and the outer shell, a rotary shaft projecting up through the axis of the mud chamber, scrapers carried by said shaft for scraping the bottoms of said liquid chamber and of said mud chamber, means for rotating said shaft, and means for carrying off the mud and liquid contents from the bottom of said mud chamber.

5. A clarifier for saccharine solutions comprising an outer shell having a central cylindrical liquid chamber with a downwardly inclined conical bottom open at its center, a lower mud chamber in the form of an inverted hollow truncated cone, below said bottom, and an upper scum chamber in the form of a truncated hollow cone, means for supplying the liquid to be clarified to said scum chamber, means for heating the liquid in said scum chamber, a series of inverted truncated hollow baffle cones projecting downwardly into said shell, and each provided with a cylindrical band at its lower open end, means for carrying off the scum from said overflow cone, means for carrying off the clear liquid from the upper portions of the V-shaped annular spaces between said baffle cones and the outer shell, a rotary hollow perforated shaft projecting up through the axis of the mud chamber, scrapers carried by said shaft for scraping the bottoms of said liquid chamber and of said mud chamber, means for supplying water under pressure to said shaft, means

for rotating said shaft, and means for carrying off the mud and liquid contents from the bottom of said mud chamber.

6. A clarifier for saccharine solutions comprising an outer shell having a central cylindrical liquid chamber with a downwardly inclined conical bottom open at its center, a lower mud chamber in the form of an inverted hollow truncated cone, below said bottom, and an upper scum chamber in the form of a truncated hollow cone, means for supplying the liquid to be clarified to said scum chamber, means for heating the liquid in said scum chamber, a series of inverted truncated hollow baffle cones projecting downwardly into said shell, and each provided with a cylindrical band at its lower open end, means for carrying off the scum from said overflow cone, means for carrying off the clear liquid from the upper portions of the V-shaped annular spaces between said baffle cones and the outer shell, a rotary shaft projecting up through the axis of the mud chamber, scrapers carried by said shaft for scraping the bottoms of said liquid chamber and of said mud chamber, means for rotating said shaft, and means for carrying off the mud and liquid contents from the bottom of said mud chamber.

7. A clarifier for saccharine solutions comprising an outer shell having a central cylindrical liquid chamber with a downwardly inclined conical bottom open at its center, a lower mud chamber in the form of an inverted hollow truncated cone, below said bottom, and an upper scum chamber, means for supplying the liquid to be clarified to said scum chamber, a series of inverted truncated hollow baffle cones projecting downwardly into said shell, means for carrying off the scum from said scum chamber, means for carrying off the clear liquid from the upper portions of the V-shaped annular spaces between said baffle cones and the outer shell, a rotary shaft projecting up through the axis of the mud chamber, scrapers carried by said shaft for scraping the bottoms of said liquid chamber and of said mud chamber, means for rotating said shaft, and means for carrying off the mud and liquid contents from the bottom of said mud chamber.

8. A clarifier for saccharine solutions comprising an outer shell having a central cylindrical liquid chamber with a downwardly inclined conical bottom open at its center, a lower mud chamber in the form of an inverted hollow truncated cone, below said bottom, and an upper scum chamber, means for supplying the liquid to be clarified to said scum chamber, means for heating the liquid in said scum chamber, a series of inverted truncated hollow baffle cones projecting downwardly into said shell, means for carrying off the scum from said scum chamber, means for carrying off the clear liquid from the upper portions of the V-shaped annular spaces between said baffle cones and the outer shell, a rotary hollow perforated shaft projecting up through the axis of the mud chamber, scrapers carried by said shaft for scraping the bottoms of said liquid chamber and of said mud chamber, means for supplying water under pressure to said shaft, means for rotating said shaft, and means for carrying off the mud and liquid contents from the bottom of said mud chamber.

9. A clarifier for saccharine solutions comprising an outer shell having a central cylindrical liquid chamber with a downwardly inclined conical bottom open at its center, a lower mud chamber in the form of an inverted hollow truncated cone, below said bottom, and an upper scum chamber, means for supplying the liquid to be clarified to said scum chamber, a series of inverted truncated hollow baffle cones projecting downwardly into said shell, means for carrying off the scum from said scum chamber, means for carrying off the clear liquid from the upper portions of the V-shaped annular spaces between said baffle cones and the outer shell, a rotary hollow perforated shaft projecting up through the axis of the mud chamber, a dispersion cone at the upper end of said shaft, scrapers carried by said shaft for scraping the bottoms of said liquid chamber and of said mud chamber, means for supplying water under pressure to said shaft, a worm and worm wheel for rotating said shaft, and means for carrying off the mud and liquid contents from the bottom of said mud chamber.

RAFAEL VACHIER.
